CLAIM

The ornamental design for a combined key holder and remote control transmitter, as shown and described.

DESCRIPTION

FIG. 1 is a perspective view of a combined key holder and remote control transmitter showing my new design; FIG. 2 is a top plan view of the design of FIG. 1; FIG. 3 is a front elevational view of the design of FIG. 1, in which a slidable button cover is illustrated in the covered position to the left;

FIG. 4 is a left side elevational view of the design of FIG. 1;

FIG. 5 is a right side elevational view of the design of FIG. 1;

FIG. 6 is a rear elevational view of the design of FIG. 1;

FIG. 7 is a bottom plan view of the design of FIG. 1; and

FIG. 8 is a perspective view of the design of FIG. 1 similar to that shown in FIG. 1, but with the button cover in its uncovered position moved to the right, FIG. 1 illustrating this button cover in its covered position.
